UNITED STATES PATENT OFFICE

95,075

DESIGN FOR A NIGHTGOWN

Alexander N. Saab, New York, N. Y.

Application November 16, 1934, Serial No. 54,051

Term of patent 3½ years

To all whom it may concern:

Be it known that I, Alexander N. Saab, a citizen of the United States of America, residing in Manhattan, county of New York, and State of New York, have invented a new, original, and ornamental Design for a Nightgown, of which the following is a specification, reference being had to the accompanying drawing, forming part thereof, wherein,

I claim:

The ornamental design for a nightgown, substantially as shown and described.

ALEXANDER N. SAAB.
